(57) **CLAIM**

The ornamental design for a bicycle helmet as shown and described.

DESCRIPTION

FIG. 1 is a left plan view of a bicycle helmet embodying the design.

FIG. 2 is a right plan view of the design shown in FIG. 1.
FIG. 3 is a perspective view of the design shown in FIG. 1.
FIG. 4 is a front elevation view of the design shown in FIG. 1.

FIG. 5 is a top elevation view of the design shown in FIG. 1; and,
FIG. 6 is a rear elevational view of the design shown in FIG. 1.

The broken lines in the drawings illustrate portions of the bicycle helmet that form no part of the claimed design.
The bicycle helmet shown in FIGS. 6 and 7 is identical to the bicycle helmet shown in FIGS. 12-17, with the exception that only the edges and boundaries shown in solid line in the illustrated left and right plan views of FIGS. 6 and 7 are being claimed. No other portions of the overall bicycle helmet are being claimed in the embodiment of FIGS. 6 and 7.

The bicycle helmet shown in FIGS. 8 and 9 is identical to the bicycle helmet shown in FIGS. 12-17, with the exception that only the edges and boundaries shown in solid line in the illustrated left and right plan views of FIGS. 8 and 9 are being claimed. No other portions of the overall bicycle helmet are being claimed in the embodiment of FIGS. 8 and 9.

The bicycle helmet shown in FIGS. 10 and 11 is identical to the bicycle helmet shown in FIGS. 12-17, with the exception that only the edges and boundaries shown in solid line in the illustrated left and right plan views of FIGS. 10 and 11 are
